UNITED STATES PATENT OFFICE.

CHARLES L. NEIN, OF ALLENTOWN, PENNSYLVANIA, ASSIGNOR TO INTERNATIONAL MOTOR COMPANY, OF NEW YORK, N. Y., A CORPORATION OF DELAWARE.

DOUBLE-ACTING TAIL GATE FOR DUMP TRUCKS.

Application filed February 1, 1927. Serial No. 165,057.

This invention relates to tail-gates for dump trucks and to hinging and locking means therefor. More especially, there is contemplated the provision of what may be termed a double acting tail-gate, for use on dump trucks or similar vehicles, having means at both upper and lower corners for holding the gate in proper position on the body. These means also serve the purpose of hinges when it is desired to open the gate, either the upper or lower edge swinging outwardly and downwardly or upwardly according to the work which is to be accomplished. A system of links and levers is provided so that the locks at both ends of the gate may be released simultaneously. The locks on the lower edge of the gate may be controlled from a point near the forward end of the vehicle body or they may be so arranged as to release the gate automatically when the dump body has been raised to a predetermined height. The locks at the top of the gate may be arranged as snap locks and various other improvements may be incorporated as will appear in the following detailed description, read in connection with the accompanying drawings, in which:

Figure 1 is a view in side elevation of a tail-gate according to the invention showing the locking means and actuating mechanism therefor.

Figure 2 is an end elevation showing the tail-gate and locking mechanism shown in Figure 1.

Figure 3 is a view partly in section taken along the line 3—3 in Figure 2 and looking in the direction of the arrows and showing in detail the means of locking the lower end of the gate.

Figure 4 is a view, partly in section, taken along the line 4—4 in Figure 2 and looking in the direction of the arrows and showing in greater detail the means for locking the upper end of the gate.

Figure 5 is a view showing a modification of the actuating mechanism for the lock at the lower end of the gate and showing a means for automatically releasing the lock when the vehicle body has been raised to a predetermined height.

In Figure 1 there is illustrated at *a* the rear end of a dump truck body to which the tail-gate *g* is to be applied. There is fastened to each end of the top of the tail-gate *g* a pin *p* by means of the brackets *c* which are

fixed upon the tail-gate as by the rivets *d*. Pins *p'* are similarly attached at each end of the bottom of the tail-gate as by the brackets *c'* and the rivets *d'*.

At each end of the top of the dump body 60 are riveted the rests *f* which are bifurcated as at *f'*, *f''*. Between the bifurcated ends of the rests *f* are pivoted locking hooks *l* as by the pintle *l'*. At one end of the hook *l* there is pinned a link *m* as by the pin *m'*. 65 Over the end of the link *m* is disposed the sleeve *m'* which abuts against the end of the stop *m''* on the end of the link. Within the sleeve *m'* is disposed a spring *m'''* and in the end of the sleeve is threaded the link *m'''* 70 which is pinned to one end of the bent lever handle *n*. The bent lever handle *n* is keyed to the shaft *n'* which is journaled in bearings *n''* at both sides under the body. At the other side of the body the shaft *n'* is connected with the locking hook *l* in an identical manner as that just described except that the handle lever *n* may be omitted.

At both ends of the bottom of the dump body are riveted the rests *e*. The bent 80 hooks *h* are pinned at one side of the rests *e* to the body by the pins *h'*. The bent hooks *h* have portions *h''* formed on the inner side thereof for a purpose which will become more apparent hereinafter. To the other end of the bent hook *h* is pinned the link *i* as by the pin *i'* and this link is in turn pinned to an arm *j* keyed to the shaft *k* which is journaled in bearings *k'* carried with the body. The shaft *k* also has keyed thereto 90 the arm *r* to which is pinned the rod *s* which extends to the under portion of the forward part of the dump body *d* and is pinned to one arm of the bent lever *t* as at *s'*. The bent lever *t* is pinned as at *t'* to a 95 bracket *t''* carried with the vehicle body.

From the foregoing description the action of the arrangement will be apparent. If it is desired to open the tail-gate by releasing the top all that is necessary is to pull downwardly on the handle *n*. This will swing the hooks *l* about the pivots *l'* releasing the pins *p* at the top of the gate and permitting the latter to swing downwardly about the pins *p'* at the bottom of the gate. When it 100 is desired to close the gate the hooks *l* may be returned to locking position first and the gate then swung upwardly. The pins *p* will press against the inclined edges *l''* of the hooks raising the latter against the action of 110

- the spring m^3 and permitting the pins p to pass beneath the point l^4 and into position. The hooks will then snap back into locking position due to the action of the spring m^3 .
- 5 It will be noted that the hooks l are prevented from inadvertently releasing the pins p , except when the handle n is pulled downwardly, due to the "past center" condition of the link m and the arm n^8 which thus forms 10 an effective locking means.
- When it is desired to open the tail-gate by releasing the bottom, which will usually be the case when the body is being used for dumping purposes, all that is necessary is to 15 pull rearwardly on the handle t , which forces the rod s rearwardly revolving the shaft k , upon which are keyed the arms j , which in turn release the pins p' by swinging the hooks h about the pivots h' through 20 the rods i . The gate will swing outwardly of itself, the body having been previously raised upon screw jacks, about the pins p at the top of the gate. When it is again desired to close the gate the gate may be 25 brought into an almost closed position and the handle t then pulled rearwardly which will bring the edges h^3 on the portions h^2 of the hooks h into contact with the pins and force the gate into completely closed 30 position. It will be noted that the hooks h are prevented from inadvertently releasing the pins p' by the "past center" condition of the rods s with relation to the arm t^2 on the handle t which thus forms an effective lock.
- 35 If desired the hooks h may be provided with automatic releasing means (Figure 5) whereby the pins p' may be released automatically when the body has been elevated to a predetermined height about the pivot x 40 carried on the chassis frame y . The arm r keyed to the shaft k has pivotally pinned thereto a buckle s^2 which is attached to a point on the chassis frame as by the chain s^3 . The arm r is held in the position indicated in the drawings against the action 45 of the spring z by the chain s^3 . It will be apparent that when the forward part of the body is raised about the pivot x the rearward part of the body will move downwardly 50 releasing the tension on the chain s^3 and allowing the spring z to pull the arm r

to the right, thereby turning the shaft k and dropping the hooks h downwardly to release the pins p' .

It will thus be seen that there has been provided for use on dump truck bodies a double acting tail-gate which may be swung either upwardly or downwardly according to which of the sets of pins ordinarily used to retain it in place have been released; in which a simple, manually controlled releasing means has been supplied for the locking devices used to retain the pins on the top of the gate in place and which means may act as snap catches; and in which either manually controlled or automatic means have been provided for releasing the means to ordinarily retain the pins carried with the bottom of the gate in place. There have also been provided means for locking the hook releasing mechanisms as well as means to prevent breakage of the parts at the top of the gate when subjected to undue stresses during unloading. The entire arrangement is simple, durable and easy to operate.

Nothing that has been said in the specification is intended as a limitation upon the scope of the invention except as indicated in the appended claim.

What I claim is:

In combination with a vehicle body, a tail-gate, pins carried with the gate at the top thereof, means carried with the vehicle body to support the weight of the gate comprising rests for the pins, hooks pivotally carried with the body and adapted to engage the pins, manually operable means to disengage said hooks simultaneously and to lock said hooks in engaged position, resilient means operatively interposed between the hooks and said manually operable means whereby the hooks, previously locked in engaged position, may move to engage the pins, other pins carried with the gate at the bottom thereof, hooks pivotally carried with the body and adapted to engage the last named pins and means to disengage said last named hooks simultaneously and to lock said last named hooks in engaged position.

This specification signed this 22nd day of January A. D. 1927.

CHARLES L. NEIN.
